UNITED STATES PATENT OFFICE

2,192,047

DISCHARGE APPARATUS

Lawrence D. Miles, Ballston Lake, N. Y., assignor
to General Electric Company, a corporation of
New York

Application February 2, 1939, Serial No. 254,155

4 Claims. (Cl. 250—27.5)

The present invention relates to means for improving the operation of power discharge devices. While not limited thereto, the invention is primarily applicable to devices having cathodes 5 constituted of cadmium.

As a cathode material, cadmium has an advantage over mercury in that it is able to operate satisfactorily at a temperature much higher than the normal ambient temperature, thus simplifying the problem of heat dissipation. However, if a cadmium tube is to be operated in a conventional circuit, it has heretofore been necessary to provide means for preheating it in order to assure the existence of sufficient cadmium 15 pressure to permit starting of the tube.

My present invention provides means for avoiding this necessity, at least in connection with cadmium tubes which utilize a holding-arc to maintain the cathode spot. This result is accomplished by supplying holding-arc current of greater than normal intensity during initial starting periods and by automatically decreasing such current upon the attainment of a predetermined temperature condition.

The features which I desire to protect herein are pointed out with particularity in the appended claims. The invention itself, together with further objects and advantages thereof may best be understood by reference to the following description taken in connection with the drawing in which Fig. 1 shows the combination of a discharge device and circuit suitably embodying the invention; and Figs. 2 and 3 illustrate further applications of the invention.

Referring particularly to Fig. 1 there is shown a sealed metal enclosure 10 having therein a main anode 11 and a cathode 12. The cathode is to be understood as being constituted of cadmium and is in direct contact with the envelope 10. The anode 11 is insulated from the envelope by means of an insulating ring 14 from which it is supported. Heavy current conductors 16 and 17 which are respectively attached to the envelope and to the anode stem provide means for supplying discharge current from a suitable source (not shown).

Cadmium, the substance of which the cathode 12 consists, is a material which is solid at room temperature and which has a relatively low vapor pressure at such temperature. However, at materially higher temperatures its vapor pressure may become sufficient to sustain a low voltage discharge. Not until a temperature many degrees above the normal temperature of the atmosphere is reached does its vapor pressure be-

come sufficiently high to cause danger of a back-fire occurrence. Consequently, it is readily possible to operate a cadmium-cathode device at a temperature on the order of say, 250 degrees centigrade, whereby effective heat dissipation 5 may be accomplished by air cooling and without the need for a special cooling fluid such as water.

In the device illustrated in Fig. 1, in addition to the main anode 11, there are provided two keep-alive electrodes 19, 20, which serve in combination with an A. C. supply to maintain a holding-arc to the cathode surface. These keep-alive electrodes are insulating supported from the top of the envelope 10 by means of lead-in seals 21 and 22. They may be replaced, of course, by 15 a single anode supplied from a direct current source.

The holding-arc current required to maintain a cathode spot during normal operation is inadequate for this purpose when the device is cold, 20 due primarily to the low vapor pressure of cadmium at room temperature. For this reason, it is generally considered necessary to preheat a cadmium-cathode device before placing it in operation. In order to avoid this necessity, my 25 invention provides means for supplying a relatively intense holding-arc current during initial starting periods and for automatically decreasing such current when the device has come up to its working temperature. The means by which this 30 is accomplished may best be understood by referring to the energizing circuit shown in the drawing.

The holding-arc current is supplied by means of a transformer 24 which has the terminals of its secondary respectively connected to the electrodes 19 and 20. The midpoint of this secondary is connected to the cathode 12 by being grounded to the envelope 10 as indicated at 25. In series with the grounding connection there is provided a resistance heater 27 which is thermally associated with the anode 11 and the function of which will be more fully explained hereinafter. For initially starting the cathode spot, one may employ an immersion starting electrode of the 40 character described in Slepian and Ludwig Patent No. 2,069,283, granted February 2, 1937.

An electrode of this type is indicated in dotted outline at 28. With the circuit arrangement so far described, it will be seen that as 50 alternating current is supplied to the transformer 24 from a suitable source (not shown), full wave rectification occurs so that current flows from the cathode 12 first to one holding anode and then to the other, thus maintaining the 55

cathode spot. The circuit impedance is such that during starting operation, when the cathode 12 is cold, the magnitude of the holding arc current is nevertheless great enough to sustain the cathode spot. In order that the holding arc current may be reduced to a more economical value when the device has reached its normal operating temperature, there is provided a temperature-responsive control means in good heat-exchanging relationship with some portion of the device. In the arrangement illustrated, such a control means, indicated by the numeral 29, is shown as being positioned in the vicinity of the anode 11 so as to be affected mainly by the temperature of that element.

The device 29 may include, for example, a thermostat having a stationary contact 30 and a movable contact-bearing element 31 which is adapted to flex under the influence of heat. The movable element should be so biased as to be open when cold and to close when hot. In circuit with the temperature-responsive device and under the control thereof, there is provided a suitable circuit-regulating apparatus illustrated by way of example as a saturable core reactor 33. This includes a load winding 34, a saturating or control winding 35 and a saturable core 36. The winding 35 is in shunt with the thermostat contacts 30, 31 and carries the holding arc current when these contacts are open. Instead of a saturable core reactor, one may, of course, employ some other type of variable impedance element, such, for example, as a controllably conductive discharge tube.

From a consideration of the foregoing, it will be understood that the impedance presented by the regulating apparatus 33 is lowest when the core 36 is in its saturated condition; that is to say, when the contacts 30, 31 are open. Since this condition corresponds to a starting period of the discharge device, the holding arc current is necessarily greatest when this condition obtains. However, as soon as the temperature of the envelope 10 has increased sufficiently to cause the contacts to close, thereby shorting the saturated winding 35, the impedance of the reactor increases and the holding arc current is correspondingly decreased. The decreased current will nevertheless be sufficient to maintain the cathode spot because of the increased temperature of the cathode 12.

In order to hasten the temperature rise of the discharge device and also as a precaution against the possibility of cathode material condensing on the anode, I may employ the resistance heater 27. By acting directly on the anode 11 this heater indirectly affects the general temperature of the discharge device as a whole. In order that the heater 27 may be controlled in a desired manner, I prefer to connect it in series with the holding arc circuit as shown so that its temperature is proportional to the holding arc current. With this arrangement the action of the control device 29 in decreasing the holding arc current is simultaneously effective to reduce the supply of heating current to the heater 27. This is a desirable result since the normal action of the load current may be relied upon to maintain the temperature of the device at a desired level as soon as a stable operating condition has been attained. Of course, if the temperature of the device falls again for any reason, as, for example, because of a temporary shut down, the control means described

will operate automatically to increase the energization of the heater.

In some cases, it is desirable not only to decrease the heat supplied to the device after a normal operating condition has been reached, but also to provide means for additionally cooling the device so as to accommodate greater load currents. The control system which I have described may also be employed to place such a cooling system in operation concurrently with the deenergization of the heating means and the reduction of the holding arc current.

In Fig. 2 I have illustrated one arrangement by which the result last indicated can be accomplished. In this case the holding arc circuit includes in addition to the heater 27, (indicated in dotted outline), a relay 40 which has its terminals in normally closed position. This relay in turn controls the energization circuit of a fan 42 or other cooling means provided in connection with the envelope 10. With the circuit connection shown, as long as the holding-arc current is maintained at its initial or starting value the relay 40 will be held open. However, as soon as the control device 29 operates to decrease the holding arc current the relay 40 will close, putting the fan 42 in operation. As previously explained in connection with Fig. 1 the anode heating current will be simultaneously reduced to a low value.

The feature described in the foregoing is applicable to any means for controlling the supply of cooling medium to the discharge device and in Fig. 3 I have shown its application in connection with a mechanical control. In this case, a relay 45, which corresponds in function to the relay 40 of Fig. 2, acts to open and close a valve 46 provided in a conduit 47 through which cooling fluid is supplied to the device 10. It will be understood, of course, that the arrangement is such that the valve 46 is closed during starting periods but is opened by the action of the relay 45 as soon as the holding arc current is decreased.

While I have described my invention in connection with particular embodiments thereof, numerous modifications may be made by those skilled in the art without departing from the invention. For example, the control means for the heating current and the holding-arc may be made to provide a continuous inverse variation of these quantities with temperature. I, therefore, aim in the appended claims to cover all such equivalent variations as fall within the true scope of the foregoing disclosure.

What I claim as new and desire to secure by Letters Patent of the United States is:

1. In combination, a discharge device having a main anode, a cathode and means for producing a continuous holding arc to the cathode, the cathode being of such character that the holding-arc current required to sustain an arc thereto is a function of cathode temperature, means for supplying a relatively intense holding-arc current during starting periods of the device and temperature-responsive means for automatically decreasing the holding-arc current to a stable operating value after a predetermined temperature condition has been attained.

2. In combination, a discharge device having a main anode, a cathode, and means for producing a holding arc to the cathode, the cathode being of such character that the current required to sustain an arc thereto is a function of cathode temperature, a resistance heater in heat-

- exchanging relation with a portion of the device, means for supplying a relatively intense holding-arc current during starting periods of the device and for supplying a predetermined heating current to the heater during such periods, and temperature-responsive means for automatically and simultaneously decreasing both the holding-arc current and the heating current upon the attainment of a desired temperature condition.
- 5 3. In combination, a discharge device having a main anode, and a cathode comprising a mass of cadmium, a resistance heater thermally associated with the device, a circuit for establishing a holding arc to the cathode, means for supplying current serially to the said heater and holding arc circuits during an initial starting period, and means for substantially decreasing such cur-
- rent upon the attainment of a desired temperature condition.
4. In combination, a discharge device having a main anode, a cathode and a keep-alive electrode, the cathode being of such character that the current required to maintain a holding arc thereto is a function of cathode temperature, means effective when energized to cool at least a portion of the device, means for supplying a relatively intense holding arc current to the keep-alive electrode during starting periods, and temperature-responsive means for simultaneously decreasing the holding arc current and energizing the said cooling means upon the attainment of a predetermined temperature condition 15 of the device.

LAWRENCE D. MILES.
